MOTOR SHROUD FOR A ROTARY LAWNMOWER

Larry Monroe Cognata, Nashville, Tenn., assignor to The Murray Ohio Manufacturing Company, Brentwood, Tenn.

Filed Sept. 17, 1974, Ser. No. 507,139

Term of patent 14 years

Int. Cl. D15—03

U.S. Cl. D40—1 B

Fig. 1.

Fig. 2.

Fig. 3.

Fig. 4.

Fig. 5.

FIG. 1 is a front perspective view of a motor shroud for a rotary lawnmower showing my new design, the view being taken from one side of the shroud;

FIG. 2 is a front perspective view thereof taken from the side of the shroud opposite that of FIG. 1;

FIG. 3 is a top plan view thereof;

FIG. 4 is a front elevational view thereof;

FIG. 5 is a rear elevational view thereof;

FIG. 6 is a side elevational view thereof taken from the same side as in FIG. 1; and

FIG. 7 is a side elevational view thereof taken from the same side as in FIG. 2.

I claim:

The ornamental design for a motor shroud for a rotary lawnmower, substantially as shown.
